UNITED STATES PATENT OFFICE.

ALBERT D'W. WELTY, SR., OF RENO, NEVADA.

PAINTER'S GUARD.

1,158,348.

Specification of Letters Patent. Patented Oct. 26, 1915.

Application filed August 12, 1914. Serial No. 856,469.

To all whom it may concern:

Be it known that I, ALBERT DE WITT WELTY, Sr., a citizen of the United States, residing at Reno, in the county of Washoe and State of Nevada, have invented certain new and useful Improvements in Painters' Guards; and I do hereby declare the following to be a full, clear, and exact description of the invention, such as will enable others skilled in the art to which it appertains to make and use the same.

This invention relates to painters' guards, and one of the principal objects of the invention is to provide a device of simple construction to be held in one hand by a painter to prevent dabbing paint upon the window panes in painting the sash or to prevent smearing of paint on papered or calcimined walls in painting around the window frames or the base-board.

Another object of the invention is to provide a guard having a plain sharp edge to bear against the edge of the surface to be painted and said guard being provided with grooves for catching the paint which may be applied to the guard by accident and said grooves being of a form to prevent the paint from smearing the work.

The foregoing and other objects may be attained by means of the construction illustrated in the accompanying drawings, in which:

Figure 1 is a front plan elevation of the painter's guard made in accordance with this invention, Fig. 2 is a similar view in which the cover for the lower edge is removed, Fig. 3 is a sectional view taken on the line 3—3 of Fig. 1 looking in the direction indicated by the arrow, Fig. 4 is a sectional view taken on the line 4—4 of Fig. 1, and Fig. 5 is a detail sectional view of the edge of the guard taken on a larger scale.

Referring to the drawings, the numeral 1 designates the blade of the guard preferably made of metal, and having one plain side 2, and the front side is provided with grooves 3 at the side, said grooves running from the outer edges 4 of the blade end, in an inclined direction and terminating at the end 5 of a longitudinal groove 5. The groove 5 is provided with an inclined wall 6, and an inwardly and downwardly inclined bottom 7

to prevent the paint from running over the outer edge of the groove 5. The rear side 2 at the working edge is provided with a bevel 8 and a sharp terminal edge 9 which is straight from end to end of the tool and adapted to lie close to the edge of the surface to be protected.

A handle 10, preferably round in cross section is provided with a longitudinal groove in which the blade 1 is fitted, and rivets 11 extend through the handle 10 and through the blade for holding the handle in place. The working edge of the tool is provided with a protector 12 which may be formed either of wood or metal and provided with a groove which would inclose the lower edge of the blade and thus prevent the same from being bent or injured when not required for use.

From the foregoing it will be obvious that a painter's guard made in accordance with this invention can be produced at low cost, is exceedingly simple in construction, can be used to advantage by amateur painters or housewives in doing painting about the window sash and other places where they are liable to smear the wall papering or other finished work.

Various changes may be made in the details of construction without departing from the spirit and scope of the invention as defined in the claim.

What is claimed is:

A painter's guard comprising a flat blade having a smooth surface upon one side and provided with a bevel at its lower edge, the opposite side of the blade being provided with grooves extending from the outer edges of the blade in an inclined direction, and a longitudinal groove disposed near the edge of the blade and terminating in the inclined grooves, said longitudinal groove comprising an inclined wall, and an inwardly and rearwardly inclined bottom, said blade being provided with a handle.

In testimony whereof I affix my signature in presence of two witnesses.

ALBERT D'W. WELTY, SR.
